UNITED STATES PATENT OFFICE

173,201

STRAINER OR THE LIKE

Francis E. Gruber, St. Paul, Minn., assignor to Brown & Bigelow, St. Paul, Minn.

Application November 13, 1953, Serial No. 27,582

Term of patent 14 years

(Cl. D44—29)

To all whom it may concern:

Be it known that I, Francis E. Gruber, a citizen of the United States, residing in St. Paul, county of Ramsey, and State of Minnesota, have invented a new, original, and ornamental Design for a Strainer or the like, for which the following is a specification, reference being had to the accompanying drawings forming part thereof.

and

Figure 4 is a bottom plan view thereof.

I claim:

The ornamental design for a strainer or the like, as shown.
